HYDRANT

Herbert M. Lofton and Earl E. Cline, Chattanooga, Tenn., assignors to Columbian Iron Works, Chattanooga, Tenn., a corporation of Tennessee

Application April 8, 1935, Serial No. 15,322

4 Claims. (Cl. 137—13)

This invention relates to hydrants, and particularly to fire hydrants having independent inside gates, i. e., a valve for each hose nozzle.

A particular feature of the present invention resides in the utilization of a single operating means for simultaneously (1) lifting the gate or valve axially from its seat on the hose nozzle and (2) moving it laterally of the hose nozzle opening.

Another feature of the invention resides in employing an adjustable mounting for such single operating means, namely, the gate or valve operating stem, such mounting including, for example, a threaded bushing whereby only a simple short turning, e. g., 90°, of the stem is necessary to clear the nozzle opening and render the water supply instantly available; moreover, a very positive opening and closing of the hose nozzle opening is achieved.

Another object is to provide, in lieu of an adjustable mounting for the stem, a construction including a nozzle having an inclined seat, in association with a valve having a rocking mounting on the end of its shaft or stem.

In addition, the gate or valve has a compensating connection with the operating stem so that any inequalities in either the valve or the seating surface will be rendered negligible, assuring a perfect seal at all times.

The main valve of the hydrant, as well as the gate operating stem, are seated and unseated by turning the respective stems on their respective threaded mountings through the medium of the usual squared wrench receiving portion or cap nut associated with the operating stem; in the present invention, these wrench receiving portions are of the same dimension and contour and have the same threaded relation. A single wrench is used to operate either valve, and the operating motion, i. e., the direction of turning to seat and unseat the valve or gate is the same in each case. This is a very advantageous factor, and combined with the feature of having the gate unseated by a short turn of the operating stem, makes the hydrant quick acting. Since it is recognized that the first seconds of a fire are the most vital, the importance of these improvements will be appreciated.

The construction is durable and dependable, free of parts which would have a tendency to normally break or wear, and is characterized by simplicity in construction.

Other objects and advantages of the invention will be more fully pointed out hereinafter.

Referring to the drawings:

Figure 1 is a partial vertical section through the hydrant.

Figure 2 is a horizontal section on the line 2—2 of Figure 1.

Figure 3 is an end view of the wrench receiving portion of the gate operating stem.

Figure 4 is a vertical section of a preferred form of the invention.

Figure 5 is a similar view of a modification, and

Figure 6 is a detail elevational view of the valve and nozzle seat of Figure 5.

Referring to Figures 1 and 4 of the drawings, the numeral 10 designates a fire hydrant having the usual bonnet 11 and lower connecting portion 12 communicating with the water main.

The main valve for controlling the water supply from the main to the hydrant is indicated at 13 and is adapted to engage a seat 14 provided on the connecting portion 12. This valve is adjustably carried by a stem 15 threadedly mounted in a suitable bushing in the bonnet 11, and at its outer end, the stem is provided with a wrench receiving portion or cap nut 16 for turning the stem to seat and unseat the valve 13.

A nozzle outlet is indicated as a whole at 17, and includes a cylindrical flange portion or boss 18 integral with the hydrant. Within the opening defined by the flange portion 18 is disposed the cylindrical nozzle 19 having a shoulder 20 forming a valve seat 21. This nozzle is inserted through the opening defined by the circular flange 18, from the inside of the hydrant, so that the circular shoulder 20 of the nozzle engages a circular shoulder 22 on the wall 18. Thereafter, the nozzle is leaded and calked into position in the usual manner, the outer end of the nozzle projecting beyond the wall 18 and having a threaded portion receiving the usual cap 23 provided with a wrench receiving portion 24.

We provide for each nozzle an independently operable inside gate or valve indicated as a whole at 25. As many nozzles 19 and gates 25 with associated operating means indicated as a whole at 26 may be provided as desired. The operating means is preferably disposed in a plane above or below the plane of the nozzles and a most satisfactory position is above and in the same vertical plane as shown in Figure 4. In Figure 1, the operating means and nozzles are in the same horizontal plane.

Referring to Figures 2 and 4, the gate operating mechanism includes a cylindrical flange por-

tion or bearing housing 27 integrally formed with the hydrant 10 and extending at substantially a 22° angle in Figure 4, and at approximately a 45° angle in Figure 2 to the integral 5 bass 18. This cylindrical flange portion is provided at one end with a shoulder 28 against which seats a suitable packing 28'. A sleeve 29 internally threaded with a relatively steep thread as shown at 30 is disposed within the 10 flange 27 and at one end abuts said packing 28'. At its other end, the sleeve is recessed, as shown at 31, to receive a packing, preferably a leather packing 32, which is doubled upon itself and within which is disposed a resilient member acting to spread the opposite sides of the packing 15 respectively against the adjacent wall of the recess 31 and the surface of the gate operating or valve stem 33 which extends through said sleeve 29 and carries the valve 25.

20 The gate or valve 25 has an adjustable or compensating connection with the valve stem 33, in the present instance, by means of a ball and socket joint including the ball member 34 carried by the valve and working in a recess 35 formed in the end of the valve operating rod 33. The ball has a stem 36 projecting through an 25 opening in the bottom of the recess 35 upon which is threaded a suitable nut 37 for securing the valve or gate operatively to the valve stem 33 and permitting the desired adjustment of the 30 valve relative to the valve operating stem 33. This is desirable in that there may be slight inequalities present in either the valve, the seat or the stem, and the compensating connection 35 will enable the valve to be adjusted to accommodate itself to any conditions of this character.

The valve stem 33, as shown, has a bent portion or foot 38 of required angle, on one end of which is carried the valve 25, and the body of the 40 stem has a threaded portion 39 of similar steep pitch with the threads 30 on the sleeve 29 with which they engage. The threads 30 and 39 are sufficient to effect the necessary seating and unseating of the valve to close and open the nozzle 45 and only turns of 90° of the stem are necessary to completely open the nozzle and thereby render the water supply instantly available.

At its outer end, there is connected to the stem 50 by a screw 40, a wrench receiving portion or cap nut 41 carrying an integral stop lug 42, as shown in detail in Figure 3. The outer end of the flange 27 is provided with an integral stop having shoulders 43 adapted to be engaged by the lug 42 to limit the turning movement of the valve stem to 55 open and close the gate or valve.

In assembling the construction, the gate 25 and stem 33 in connected relation are inserted in the opening defined by the flange or boss 28 from the inside of the hydrant. Thereupon, the packing 28' is positioned on the shoulder 28 and sleeve 29 is inserted through the outer open end of the flange 27, the sleeve being threaded on the stem until contact of the sleeve with the gasket 28' is established, preferably by means of a suitable spanner wrench engaging in recesses 60 in the end of the sleeve. Then the sleeve is further revolved until the valve or gate 25 is seated on the valve seat 20 and again until the independent gate or valve 25 is firmly seated in a closed position. Thereafter the packing 32 is 65 inserted in the recess 31 in the sleeve and then a lock nut 44 having spanner wrench receiving openings 45 therein is threaded into the internal threads 46 on the flange 27 and screwed up firmly 70 against the end of the sleeve 29 to fix it in position.

75 The cap nut 41 is now fixed to the stem 33 by means of the bolt 40.

It will be seen that the mounting for the stem 33, including the sleeve 29, provides a convenient means for regulating or adjusting pressure of the 5 valve 25 on its seat. That is, not only may the seating pressure of the valve on its seat be regulated when the assembly is mounted, but after the valve has been in use for a time, the seating pressure may be adjusted by tightening 10 or loosening the pressure of the sleeve 29 against the shoulder 28.

The cap nuts 16 and 41 are substantially similar in size and contour and this is likewise true of the nozzle cap 24. Hence a single wrench need 15 only be employed. Again the threaded mountings of the main valve stem 15 and operating stem 33 are the same, i. e., both left or right hand threads, which is also the case with the threaded nozzle cap 24, so that each of the cap nuts and 20 the cap will be turned in the same direction and by the same tool, thus minimizing any possibilities of confusion at the scene of a fire.

In the operation of the hydrant, the cap 23 is 25 removed and the hose threaded on the nozzle in the usual manner. Thereafter, the stem 33 is turned in its mounting in the fixed sleeve 29 which will simultaneously act (1) to lift the valve or gate 25 axially from its seat 21 and (2) move it laterally, e. g., upwardly in Figure 4, or upwardly or downwardly in Figure 1 (in accordance with whether left or right hand threads are used) to a position approximately 90° from the closed position as shown in Figure 1 where the valve is displaced upwardly. Because of the 30 steepness of the pitch of the threads, the nozzle is opened by a simple, quick and short positive turning movement of the gate operating stem, i. e., about 90°, and hence the water is made instantly available. The main valve 13 is, of course, 35 opened either prior to releasing the nozzle gate or may be opened subsequently thereto as where a hose breaks or an additional hose is hooked up to the hydrant.

It will be noted that a single positive means is 40 employed for simultaneously moving the valve or gate 25 axially and laterally with relation to the nozzle seat 21 and the construction is devoid of any parts which might under the normally strenuous conditions surrounding the use of the 45 hydrant, be subject to wear and breakage. The hydrant is, therefore, dependable and durable and this sturdy construction is achieved with 50 simplicity; moreover, the hydrant is quick acting as explained, and since it is axiomatic that the 55 first seconds of a conflagration are vital, this feature is of unusual importance.

The hydrant employs a separate gate 25 for 60 each nozzle and a single operating means, namely, the valve stem 33, is associated respectively with each gate for simultaneously moving the gate axially and laterally relative to the nozzle. It is to be observed that a very positive and effective seal is obtained by reason of the mechanical pressure or force exerted in closing the valve. 65 Moreover due to the adjustable mounting a very fine and critical adjustment of the pressure between the valve and seat is obtained, this being accomplished by rotating the sleeve 29 with respect to the stem 33 and against the shoulder 28. 70 The flanges or bosses 18 and 27 are preferably integral with the hydrant body casting and form horizontally disposed housings or mountings for the nozzle and valve operating mechanism, respectively. 75

Referring to Figures 5 and 6, illustrating a modification, the nozzle shoulder 20' is wedge-shaped defining an inclined valve seat 21'. The valve 25' is plane and mounted on the stem or operating rod by a ball and socket joint 34-35, as described above. If desired, the valve is made wedge-shaped and the seat plane, but an inclined seat and plane valve are preferred. The housing 27 has a bearing ring 50 and an internally threaded sleeve 51 engaging the ring. The ring opening is of less diameter than the opening in the housing through which the valve stem 33 passes and forms a lower shoulder 52. The valve stem 33 is enlarged at 53 and has a reduced extension 54, defining a shoulder 55 engaging the lower shoulder 52 formed by the ring. The reduced extension 54 has a threaded portion 56 receiving a locking sleeve 57 engaging the opposite or upper shoulder 58 provided by the ring, whereby the valve stem is fixed for rotation in the housing. In all other respects the construction of Figures 5 and 6 is similar to that previously described, except that the screw threads 56 need not be as steep as those disclosed in connection with the previously described embodiment.

In operation, a short turning of the cap nut 41, moves the valve 25' from its wedging engagement with the seat or moves the valve into wedging seated relation therewith. This wedging engagement of valve and seat assures a tight seal at all times.

We claim:—

1. A hydrant comprising a nozzle including a valve seat, a valve for said seat, a stem for operating said valve mounted for turning movement on the hydrant to seat and unseat said valve, said stem mounting including a threaded sleeve, said stem having threads engaging the threads of the sleeve, and means for regulating the seating pressure of said valve on said seat by moving said sleeve with respect to said stem.

2. In a hydrant, a casing including an outlet, a valve seat for the outlet on the inner wall of the casing, a valve for said seat within said casing, said valve being carried by an angular op-

erating stem, relatively steep threads on said stem, means for mounting said stem on said casing including a sleeve carried by said casing, and relatively steep threads on said sleeve for engaging the threads of said stem, whereby said valve 5 may be moved both axially and laterally to and from said seat when said stem is turned in said sleeve, said sleeve being mounted for rotation on said casing to permit relative movement thereof with respect to said stem to adjust the pressure 10 of said valve on said seat.

3. In a hydrant, a casing, an outlet nozzle extending through said casing from the interior to the exterior thereof, a valve seat at the inner end of said nozzle, a valve for said seat within said casing, a valve stem comprising a straight bearing portion and an angular portion within said casing, a valve stem bearing housing in said casing adjacent to and at one side of said nozzle, means for mounting said stem in said housing including a sleeve within said housing surrounding said stem, relatively steep threads on the interior of said sleeve and cooperating threads on said straight portion of said stem in engagement with the threads of said sleeve, whereby 25 said valve may be moved both axially and laterally to and from said seat when said stem is turned in said sleeve, means for maintaining said sleeve fixed with respect to said casing during normal operation of said valve, said sleeve being 30 mounted for rotation on said casing to permit relative movement thereof with respect to said stem to adjust the pressure of said valve on said seat.

4. A hydrant comprising a casing having a 35 nozzle and a valve seat at the inner end thereof within said casing, a valve for said seat within the casing, a valve operating stem having an angularly disposed foot carrying said valve and mounted in the casing adjacent to and at one 40 side of said nozzle to seat and unseat said valve, said mounting means including means for adjusting said stem for regulating the seating pressure of said valve on said seat.
